WILLIAM ROPER, OF PHILADELPHIA, PENNSYLVANIA.

METAL SASH-JOINT.

1,213,541.

Specification of Letters Patent.

Patented Jan. 23, 1917.

Application filed December 15, 1915. Serial No. 66,984.

To all whom it may concern:

Be it known that I, HENRY N. RENTON, a citizen of the United States, residing at Philadelphia, in the county of Philadelphia and State of Pennsylvania, have invented certain new and useful Improvements in Metal Sash-Joints, of which the following is a specification.

My invention relates to improvements in metal sash joints, the object of the invention being to provide a joint in which improved constructions of munnions are rigidly secured together without the use of any third part or means.

15 A further object is to provide a securely tight joint in which two munnions at right angles to each other, one constituting a T-bar and the other a cross shaped bar, are rigidly connected.

20 With these and other objects in view, the invention consists in certain novel features of construction and combinations and arrangements of parts as will be more fully hereinafter described and pointed out in the 25 claims.

In the accompanying drawings: Figure 1 is a view in cross section through one of the munnions illustrating my improved joint. Fig. 2 is a view in side elevation of munnion 1. Fig. 3 is a plan view of the joint. Fig. 4 is a view in side elevation of munnion 2. Fig. 5 is a plan view of munnion 1 in position to receive the other munnion. Fig. 6 is a view in cross section on the line 6—6 of Fig. 2. Fig. 7 is a view in cross section on the line 7—7 of Fig. 4, and Fig. 8 is a view similar to Fig. 1 illustrating a modification.

My improved joint is composed of munnions 1 and 2, located at right angles to each other. Munnion 1 is of general cross shape in cross section. In other words, the munnion 1 comprises a relatively thin web 5 provided at opposite sides with laterally projecting flanges 3. These flanges 3 extend 45 throughout the length of the munnion, are spaced from both edges of the munnion, but are preferably nearer one edge than the other as shown clearly in the drawings. Munnion 2 is of general T-shape in cross 50 section. In other words, munnion 2 comprises a relatively thin web 6 provided at one edge with oppositely projecting flanges 4 which extend throughout the length of the munnion. Munnion 2 is provided in the edge of its web 6 with a recess 7 of approxi-

mately the same width as the thickness of the web 5 of munnion 1. Munnion 1 is provided with a T-shaped opening 8 corresponding in shape to the shape of munnion 2 in cross section except that the opening 8 is of a length approximately the same as the width of munnion 2 from the inner end of the recess 7 to the flanged edge of the munnion.

The wide portion of the opening 8 is formed by cutting out the flanges 3 of munnion 1 and the long part of the opening 8 extends transversely of the web portion 5 of munnion 1. A tongue 9 is cut from the web of munnion 1 adjacent the wide portion of the opening 8, so that one wall of the tongue 9 constitutes one wall of the opening 8. The tongue 9 is located entirely within the outline of the munnion, and is of a length appreciably greater than the width of the opening 8, so that it can be bent laterally as shown in Fig. 5, and be out of the way when the munnion 2 is inserted into the opening. When this tongue 9 is bent as shown in Fig. 5, munnion 2 can be inserted in the opening 8. When the munnion is so inserted, and the recess 7 alines with the end of slot 8, munnion 2 can be moved laterally so that its recess 7 will straddle the web portion of munnion 1 between the end of slot 8, and the edge of the web. When in this position, the edges of webs 5 and 6 of the two munnions will be in alinement as shown clearly in Fig. 1, and the flanges 4 of munnion 2 will be located in the wide portion of the slot 8 of munnion 1. Tongue 9 is then bent back to its former position, so that it constitutes a part of the web of munnion 1, and securely holds munnion 2 in its joint relationship to munnion 1. It will be noted that the munnion 1 is of an appreciably greater width than munnion 2, and that the munnion 1 from its flanges 3 to one edge thereof is of the same width as munnion 2, hence the munnions when joined, have their edges at one side of the joint located in alinement. Instead of providing a single tongue 9 as shown in Fig. 2, munnion 1 may be cut so as to provide two tongues 10 as shown in the modification Fig. 8, which would be bent similar to the tongue 9 to allow munnion 2 to be inserted.

Various slight changes might be made in the general form and arrangement of parts described without departing from my in-

vention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A sash joint comprising two munnions, one having a notch in one edge, the other having a slot therein, a tongue formed in said latter munnion, said tongue being produced by forming two slits lengthwise of said munnion and another slit connecting said first slits, one long edge surface of said tongue entirely forming one end of said slot, said tongue being laterally bendable to provide space additional to said slot to permit the insertion of said first munnion, said first munnion after its insertion being movable transversely to said second munnion to permit the portion forming said notch to straddle the portion of said second munnion adjacent the opposite end of said slot, said tongue being movable into its original position after the first munnion has been moved into said straddling position, substantially as described.
2. A sash joint comprising two munnions, at angles to each other, one munnion being of general cross-shape section, the other munnion being of general T-shape transverse section, the cross shaped munnion having a T-shape opening therein into which the T-shape section fits, said cross-shape section being slit to provide a laterally bendable tongue directly adjacent the outer surface of the head portion of the T-shape munnion, the end surface of the web of the T-shape munnion having a recess into which a portion of the web of the cross-shape munnion extends to form a lock, said tongue when bent out laterally providing space in addition to said opening into which said T-shape munnion may be slid and afterward moved transversely to form said lock, said tongue when bent to its original position serving to abut said outer surface of the head of the T-shape munnion, substantially as described.

tion of the web of the cross-shape munnion extends to form a lock, said tongue when bent out laterally providing space in addition to said opening into which said T-shape munnion may be slid and afterward moved 45 transversely to form said lock, said tongue when bent to its original position serving to abut said outer surface of the head of the T-shape munnion, substantially as described.

3. A sash joint comprising two munnions at angles to each other, one munnion being of general cross-shape section, the other munnion being of general T-shape transverse section, the cross shaped munnion having a T-shape opening therein into which the T-shape section fits, said cross-shape section being slit to provide two oppositely disposed laterally bendable tongues directly adjacent the outer surface of the head portion of the T-shape munnion, the end surface of the web of the T-shape munnion having a recess into which a portion of the web of the cross-shape munnion extends to form a lock, said tongues when bent out laterally providing space in addition to said opening into which said T-shape munnion may be slid and afterward moved transversely to form said lock, said tongues when bent to their original positions serving to 65 abut said outer surface of the head of the T-shape munnion, substantially as described.

In testimony whereof I have signed my name to this specification in the presence of two subscribing witnesses.

HENRY N. RENTON.
